JOHN BELLAMY TAYLOR OF SCHENECTADY, NEW YORK.

SIGNALING SYSTEM.

1,410,626.

Specification of Letters Patent. Patented Mar. 28, 1922.

Application filed December 11, 1915. Serial No. 66,246.

To all whom it may concern:

Be it known that I, JOHN BELLAMY TAYLOR, a citizen of the United States, residing in Schenectady, county of Schenectady, 5 State of New York, have invented certain new and useful Improvements in Signaling Systems; and I do hereby declare the following to be a full, clear, and exact description of the invention, such as will enable 10 others skilled in the art to which it appertains to make and use the same.

This invention relates to signaling systems for use in indicating the relative bearing of a moving object with respect to an 15 other object, moving or stationary.

The invention is herein described with 20 reference to marine vessels, but the application to air ships, submarine boats and other moving objects will be apparent.

It has become common practice to equip 25 vessels of substantial size with wireless telegraph apparatus and such apparatus may be used by vessels nearing each other in a fog to communicate each to the other information as to the direction in which the vessel is proceeding with reference to the 30 points of the compass. But, although the receiving vessel would thus be advised of the direction in which the vessel sending the message was proceeding with reference to the 35 compass, it would not know in what position the sending vessel lay with reference to the vessel receiving the signal. As is well known, it is difficult to tell from what point a sound which is heard at sea in a fog emanates so that audible signaling devices such as fog-horns do not suffice to indicate with sufficient accuracy the position of one 40 boat with reference to another.

In the following specification I describe a 45 signaling system by which a boat may receive from another boat or from a shore station signals by which the bearing of the sending boat or shore station with reference to the receiving boat may be ascertained. The system involves the provision of two or 50 more signaling devices adapted for sending audible or other sound signals mounted upon a ship at predetermined distances apart and means for sounding these signaling devices in a definite time relation. Thus, two signaling devices may be located fore and aft of a ship, spaced apart by a distance of 545 55 feet through which distance sound will travel in one-half second. Also, the sounding apparatus for actuating the two audible

signaling devices may be so arranged as to sound the fore signaling device one-half second after the aft signal device is sounded. The sounds given by such signaling apparatus could be employed for transmitting information without the aid of special receiving apparatus upon the receiving ship. If the sending ship were proceeding directly 60 toward the receiving ship, the sounds from the two signaling devices would be heard simultaneously at any point along the line directly ahead of the receiving ship, owing to the greater distance and greater time required for sound to travel from the aft signaling device on the sending ship as compared 65 with the distance and time required for sound to travel from the fore signaling device to any point on said line, as for instance the point on such line coinciding with the position of the receiving ship at that instant. If we assume that the fore and aft signaling devices are 545 feet apart, through 70 which distance sound will travel in half a second, and the aft signaling device is arranged to be sounded exactly half a second before the fore signaling device, so far as the receiving-ship is concerned the sound from the aft signaling device of the sending-ship will reach the fore signaling device just in 75 time to merge with the sound emitted from the latter device, provided the sending-ship is approaching the receiving ship head on. If the sounds from the two signaling devices on the sending-ship are received at the receiving ship with an interval of one full 80 second between them, the operator on the receiving ship would know that the other ship is proceeding directly away from him. Thus, the length of the time interval between 85 the reception of the two signals upon the receiving ship, ranging from one second down to zero, would serve to indicate the angle at which the sending ship is heading relative to the fore and aft line of the receiving ship. 90 It may be desirable in cases where the sending ship is heading directly for the receiving ship, to ascertain the direction in which the sending ship is proceeding with reference to the compass, and wireless telegraphy 95 may be utilized for this purpose. Of course it will be understood that for theoretically accurate work, suitable correction should be made for the velocities of the two ships in 100 comparison with the velocity of sound. However, since ship speeds of from fifteen to 110 thirty miles per hour compared with the

velocity of sound, which is roughly 700 miles per hour, would indicate a maximum correction of four or five per cent, and such a correction only for some positions and velocities, this relative velocity factor may be safely disregarded in most cases.

The sounding of the two signaling devices upon the sending ship would be repeated at relatively short intervals, for instance, at 10 intervals of about ten seconds, and the variation of the time interval between the two sounds as the repetitions occurred could be readily followed and would serve to indicate with a substantial degree of accuracy and over an extended period of time, the relative positions of the two ships.

If the time interval of repetition of signals is known at the receiving station and the time interval of reception of the repeated signals is carefully noted, the speed of movement of the second ship may be estimated.

If desired, the two signaling devices provided upon the ship at a predetermined distance apart might be arranged to give sounds of different pitch and in this case, the time relation given above as to the sounding of the two signals might be varied. Then, supposing that the signaling devices were sounded simultaneously and that the source at the stern of the ship were of the higher pitch, sounds in rising pitch sequence heard on the receiving ship and emanating from the two signaling devices of the sending ship would indicate that the sending ship was proceeding toward the receiving ship, whereas, on the other hand, sounds of falling pitch sequence would indicate that the sending ship was proceeding away from the receiving ship.

In combination with such signal transmitting mechanism, I may employ mechanism for facilitating the accurate reception of the transmitted signals. The receiving mechanism may include means for recording the times of reception of the two sounds emanating from the two signaling devices on the sending ship. Such receiving apparatus may include a traveling tape actuated by a 50 chronometric mechanism together with a marker actuated in a suitable manner upon reception of the sounds. The extent of separation of the marks on the tape resulting from the two actuations of the marker would then serve to indicate the relative bearing of the sending ship. So also other more elaborate known direction-indicating sound receiving devices, such for example as the apparatus of my patent No. 939,349, may be used to supplement and check the indications deducible from the emitted sounds.

I have illustrated constructions which may be employed in the practice of the invention in the accompanying drawings, in which 65 Fig. 1 is a side view of a vessel equipped

with my improved transmitting and receiving apparatus; Fig. 2 is a diagrammatic view of the signaling devices and the mechanism for operating them; Fig. 3 is a diagrammatic view of the receiving apparatus; 70 and Fig. 4 is a view of a piece of tape with the signal marks thereon. The vessel shown in Fig. 1 is provided with two signaling devices 10 and 11, mounted at a prearranged distance apart. These signaling devices 75 are preferably bells of substantial size mounted at a distance of 545 feet apart, through which distance sound travels in one-half second. Means are provided for sounding these two signaling devices in a predetermined time relation; preferably, the bell 10 at the stern would be sounded one-half second ahead of the bell 11 at the bow. Any suitable apparatus for striking the bells in the desired time relation and repeating the 85 sounding of the bells at the desired intervals may be employed.

In the present instance, I have shown a rotating contact device 12 having contacts 13 and 14 upon its periphery adapted to coat 90 with brushes 15 and 16, whereby circuits are closed through solenoids 17 and 18. Each of these solenoids is provided with a core 19 which is connected by levers 20 with the pivoted clapper 21 of the corresponding bell. The mechanism for rotating the cylinder 12 may be such that the contacts 13 and 14 are carried under the brushes 15 and 16 once every ten seconds, and the two contacts 13 and 14 may be spaced apart 95 a distance equal to 1/20 of the circumference of the cylinder 12. This arrangement of the parts would result in striking the bells 10 and 11 once every ten seconds, the bell 10 being struck each time one-half second 100 ahead of the bell 11.

If desired, the two bells 10 and 11 may be so constructed as to give sounds of different pitch. Then the bells may be sounded simultaneously and, assuming the bell at 110 the stern to be the one of higher pitch, sounds of rising pitch sequence received at the receiving ship and emanating from the two bells would indicate that the sending ship was approaching the receiving ship. 115 On the other hand, sounds of falling pitch sequence given by the two bells would indicate that the sending ship was proceeding away from the receiving ship.

It will be appreciated that with apparatus 120 of the character indicated in Figs. 1 and 2 for sending signals from one ship to another, the sounds emanating from the two signaling devices could be received on the receiving ship without the aid of special receiving 125 apparatus. With relatively little experience, a person on the receiving ship would be able to estimate the position—that is, whether heading toward or away from the receiving ship—of the sending ship from 130

the interval elapsing between the successive sounds received from the two bells on the sending ship. However, greater accuracy may be had in determining the intervals of time between reception of the two sounds by the use of receiving apparatus. Such apparatus consists preferably of a traveling tape, markers for marking upon this tape, and manually or automatically actuated devices by which the operation of the markers may be controlled. In Fig. 3 such a receiving apparatus is shown diagrammatically for purposes of illustration the operation of the markers being controlled by manually actuated devices. A traveling tape is indicated at 22, this being unwound from the roll 23 by roller 24, the latter being arranged to be rotated by suitable chronometric apparatus 25. Between the two rolls, 10 the tape passes over a support 26, and above this support marking levers 27 and 28 are pivotally mounted and adapted to be rocked on their pivots so as to cause their marking ends to engage the tape 22. Each lever 27 and 28 has an armature fixed thereto and 15 adapted to coat with a magnet 29. Also, each magnet 29 is connected in circuit with a battery 30 and a manually actuated key 31. The traveling tape 22 is preferably provided with transverse lines spaced apart by the distance which the tape would be moved in one second by the chronometric apparatus 25.

A vessel equipped with such a receiving apparatus, if enveloped in a fog and warned by wireless telegraphy of the proximity of another vessel, would start the apparatus 25 in operation to move the tape 22. The operator would then depress the key 31 in 20 exact correspondence with the sounds reaching him from the bells 10 and 11 upon the transmitting ship and as a result, the marker 27 corresponding to that key would make a mark on the tape for each depression of key 31. The separation of two adjacent marks on the tape 22, gauged by reference to the transverse lines on the tape, the space between any two such transverse lines indicating one second of time, would serve as an 25 indication of the position of the transmitting ship with reference to the receiving ship. When the tape shows but a single mark for each signal interval of say ten seconds, the sending ship is heading directly toward the receiving ship. Where the tape shows a pair 30 of marks separated by a space equal to the space between two transverse lines on the tape or a distance corresponding to one second, the sending ship is heading directly away from the receiving ship. For intermediate positions of the sending ship relative to the receiving ship, the spaces between the successive pairs of marks will indicate the passage, of less time than one second, from which the 35 bearing angle of the sending ship may be esti-

mated by experience or ascertained by referring to a suitable scale. In this connection, it may be explained that the time value indicated by any pair of marks is not exactly proportional to the angular position of the sending ship but depends on the cosine of the angle.

The apparatus above described may advantageously be supplemented by using a plurality of receivers spaced apart on the receiving vessel, in accordance with known principles. Such arrangement is indicated by the two keys in Fig. 3, the double record marks being shown on the tape of Fig. 4.

In the foregoing description and in the drawings, the two signaling devices employed for transmitting the signals are described as mounted at a definite distance apart fore and aft of the ship. It will be understood, however, that the two signaling devices or an additional pair of signaling devices may be arranged on opposite sides of the vessel and separated by a predetermined distance, preferably as great a distance as may be conveniently obtained. If such signaling devices were employed in addition to those arranged fore and aft of the ship, they would preferably be such as would give signaling sounds readily distinguishable from those of the other pair of signaling devices. The additional signaling devices on opposite sides of the ship are for the purpose of giving additional information to check any indicated bearing, and for differentiating the two symmetrical positions on the same compass course or on the same side of the receiving ship which give the same time interval between receipt of the two signals in a given order. For example, an indication on the tape 22 to the effect that the aft signal of the sending ship is being received a certain fraction of a second later than the fore signal on the sending ship, would merely show that the sending ship is moving toward or away from the center line of the receiving ship at a certain angle. And where this angle is 90°, and the sending ship is halfway across the center line of the receiving ship, even a wireless message from the sending ship as to her compass bearing would not aid in determining whether the sending ship is passing ahead or astern of the receiving ship.

I claim:

1. A signaling system comprising the combination of sound signaling devices at a predetermined distance apart, and means for actuating the signaling devices in a definite time relation bearing a definite relation to the spaced time required for sound to travel through said predetermined distance; substantially as described.

2. A signaling system comprising the combination of two sound signaling devices at a predetermined distance apart, and

- means for sounding the two signaling devices with a time interval between them substantially equal to the time during which sound travels from one signaling device to the other; substantially as described. 5
3. A signaling system comprising the combination of sound signaling devices at a predetermined distance apart and adapted to give sounds differing in pitch, and means 10 for sounding such signaling devices in a definite time relation bearing a definite relation to the spaced time required for sound to travel through said predetermined distance; substantially as described. 15
4. A signaling system for indicating at a receiving station the angular position of a moving vessel and changes of that position, comprising two individual sound signaling devices mounted on the vessel at known separated points from which the sounds may travel to the receiving station, and means for sounding said devices in known spaced time relation, whereby the position of the vessel with respect to the receiving station may be 20 determined by comparing the time sequence of the received sounds with the known time relation of the emitted sounds; substantially as described. 25
- 5: A signaling system for sending signals from a vessel to indicate the angular posi- 30
- tion of the vessel and changes of that position, comprising two sound signaling devices adapted to give sounds differing in pitch mounted on the vessel at a predetermined distance apart, and means for actuating the signaling devices intermittently in a definite spaced time relation; substantially as described. 35
6. The method of indicating the position and direction of travel of a vessel with respect to a given point, which consists in emitting individual sounds from two known separated points on the vessel in known spaced time relation and comparing the time sequence of the sounds received at the said point with the known time relation of the emitted sounds; substantially as described. 40
7. The method of indicating the position and direction of travel of a vessel with respect to a given point, which consists in emitting individual sounds from two known separated points on the vessel in known spaced time relation, recording the time sequence of successive groups of sounds received at said point, and comparing the group records with the known time relation of the emitted sounds; substantially as described. 45

In testimony whereof I affix my signature.
JOHN BELLAMY TAYLOR.

Certificate of Correction.

It is hereby certified that in Letters Patent No. 1,410,626, granted March 28, 1922, upon the application of John Bellamy Taylor, of Schenectady, New York, for an improvement in "Signaling Systems," errors appear in the printed specification requiring correction as follows: Page 3, line 125, claim 1, strike out the word "spaced"; page 4, line 11, claim 3, before the word "time" insert the word *spaced*, and line 12, after the article "the" strike out the word "spaced"; and that the said Letters Patent should be read with these corrections therein that the same may conform to the record of the case in the Patent Office.

Signed and sealed this 16th day of May, A. D., 1922.

[SEAL.]

KARL FENNING,

Acting Commissioner of Patents.
